(57) **CLAIM**

The ornamental design for a casing for an electronic device as shown and described.

DESCRIPTION

The file of this patent contains at least one drawing/photograph executed in color. Copies of this patent with color drawing(s)/photograph(s) will be provided by the Office upon request and payment of the necessary fee.

FIG. 1 is a top plan view of a casing or an electronic device, showing my new design;

FIG. 2 is a bottom view thereof;

FIG. 3 is a front elevational view thereof;

FIG. 4 is a rear view thereof;

FIG. 5 is a right side elevational view thereof;

FIG. 6 is a left side elevational view thereof;

FIG. 7 is a right side, front, and top perspective view thereof; and,

FIG. 8 is a left side, rear, and top perspective view thereof. The broken line portion of the figure drawings is included to show portions of the article that form no part of the claimed design.
